COUPLING ELEMENT

Peter R. Hollaender, Cincinnati, Ohio, assignor to
The Hollaender Manufacturing Company, Cincinnati, Ohio, a corporation of Ohio

Application October 28, 1948, Serial No. 149,351

Term of patent 14 years

(Cl. D54—1)

To all whom it may concern:

Be it known that I, Peter R. Hollaender, a citizen of the United States, residing at Cincinnati, in the county of Hamilton and State of Ohio, have invented a new, original, and ornamental Design for a Coupling Element, of which the following is a specification, reference being had to the accompanying drawings, forming a part thereof.

Figure 1 is a perspective view of the coupling element, showing my new design.

Figure 2 is a side elevational view.

Figure 3 is an end elevational view.

I claim:

The ornamental design for a coupling element, substantially as shown.

PETER R. HOLLAENDER.
